UNITED STATES PATENT OFFICE.

ALBERT A. DAY, OF NEW YORK, N. Y.

SLIDING EXTENSIBLE SCREEN.

No. 817,471.

Specification of Letters Patent.

Patented April 10, 1906.

Application filed January 13, 1906. Serial No. 295,890.

To all whom it may concern:

Be it known that I, ALBERT A. DAY, a citizen of the United States, residing at the borough of Brooklyn, in the city of New York, county of Kings, and State of New York, have invented certain new and useful Improvements in Sliding Extensible Screens; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate one form in which I have contemplated embodying my invention and several slight modifications thereof, and said invention is fully disclosed in the following description and claims.

Referring to the said drawings, Figure 1 represents a perspective view of a screen embodying my invention. Fig. 2 is a detail view of a portion of one of the vertical frame-bars, showing the manner of inserting the wire gauze or netting. Fig. 3 is a similar view showing the bar after beading to secure the wire-netting therein. Fig. 4 is a sectional view on line 4-4 of Fig. 3. Figs. 5, 6, and 7 are detail views showing the manner of attaching the horizontal frame-bars to the vertical bars and forming the corners of the screen-sections. Fig. 8 is a transverse vertical central section through a screen formed as illustrated in Figs. 1 to 7, inclusive, the central part of the wire-netting being broken away. Figs. 9, 10, and 11 are similar views illustrating modified forms of the horizontal frame-bars, cross-sections of which are there shown. Fig. 12 is a sectional view of a slightly-modified form of screen, showing only the upper horizontal bars and illustrating their relation to a window-sash bottom rail. Fig. 13 is a view similar to Fig. 12, showing still another modified form of horizontal screen-bar.

In the manufacture of metallic screens several difficulties have been encountered in placing them on the market, among which may be enumerated that of providing a construction of sufficient lightness, strength, and durability and at minimum cost, that of properly yet economically forming the corner joints of the screen-frames, and that of securely and permanently attaching the wire fabric to the sustaining-frame.

The object of my invention is to overcome all of these difficulties and to produce a screen of great cheapness, durability, and simplicity.

In Fig. 1 I have shown my invention applied to the construction of a sliding extensible screen, in which A and A' represent two similar screen-sections, which are formed in the same manner, so that a description of one will suffice for both. In forming the screen I first take a piece of wire fabric B, cut to the required size and of rectangular shape, and to two opposite edges I attach the vertical bars C of the frame. Each of these bars C is formed of sheet metal, (preferably iron or steel and galvanized, if desired,) bent upon itself, as shown in Fig. 2, the bar C being of substantially the same length as the wire fabric. The fabric is inserted into the space between the folded portions of the bar and the bar is then beaded, crimped, or corrugated longitudinally in any desired manner to permanently unite the bar and wire fabric. I prefer to form two longitudinal bends or beads c c in the bar, as shown in Figs. 3 and 4, and I prefer that the beads should terminate a short distance from each end of the bar C, as shown in Fig. 3, leaving a plain end portion c' at each end. The bars C, having been attached to opposite edges of the wire fabric B, as just described, I attach the horizontal bars D in the following manner. Each bar D is also formed of sheet metal, like the bars C, folded upon itself, (see Fig. 5,) and is placed over one of the horizontal edges of the wire fabric, so as to inclose the plain ends c' of the vertical bars. (See Fig. 6.) The bars D are then each folded or bent longitudinally into any one of the forms shown in Figs. 8 to 13, inclusive, to securely unite to said bars D the ends of the vertical bars C C and also the horizontal marginal portions of the wire fabric, as will be clearly seen in the drawings. In bending or folding the horizontal top and bottom bars D longitudinally the ends of the vertical bars C will be transversely bent and folded within the same, thus securely locking the bars C and D together to form the corners and rendering the use of solder, rivets, or other fastening means unnecessary. If it is desired, however, the bars C and D may be further secured by any additional means, such as those enumerated or others; but I do not consider that this will be necessary, and the absence of any additional securing means will further cheapen the cost of manufacture. The top and bottom or horizontal bars are

made longer than the width of the fabric B, as shown at d, and as is usual to give greater guiding and supporting action in extending the screen. The two screen-sections are constructed alike, except that one is just sufficiently shorter vertically than the other to permit the bars D D of the screen-sections to slidingly engage each other, as shown, the bars D D of one section ordinarily lying with-
in the bars D D of the other screen-section.

In the form shown in Figs. 1 to 8, inclusive, the bars D are longitudinally folded downwardly, as at d', and then upwardly, as at d², this greatly increasing their strength, while securing the interlocking and other results enumerated.

In Fig. 9, in which the upper and lower bars are indicated by D', they are shown as folded laterally at a slight angle, as at d³, then horizontally, as at d⁴, and downwardly and inwardly, as at d⁵, thus forming a dovetailed groove which receives the other screen-section.

In Fig. 10 the horizontal bars indicated by D² are bent sharply over in the form of an inward curve, (shown at d⁶), the convex inner faces of the bars of one section engaging the concave outer faces of the bars of the other section.

In Fig. 11 the horizontal bars D³ are shown as bent in the arc of a circle slightly less in extent than a full circle, as shown at d⁷, thus forming quasi-tubular bars, which afford a firm guiding engagement between the two frames.

In Fig. 12 the horizontal bars indicated at D⁴ are bent sharply into a horizontally-inclined position, as at d⁸, and then upwardly, as at d⁹, thus, in addition to guiding and holding the two screen-sections together, forming a seat for the lower edge of the window-sash, as indicated in dotted lines.

Fig. 13 shows the horizontal bars indicated by D⁵ bent upwardly, as at d¹⁰ and then downwardly, as at d¹¹, this form being the converse of that shown in Figs. 1 to 8 and the inclined outer faces forming seats for the bottom edge of the window-sash, as indicated in dotted lines.

It is obvious that the horizontal bars can be folded in various other ways to secure the results herein enumerated and without departing from my invention.

While I have shown my invention embodied in a sliding extensible screen, I claim, broadly, the construction by which a screen-section is formed as herein shown and described whether it is used in this particular type of screen or others to which it may be adapted.

What I claim, and desire to secure by Letters Patent, is—

1. A window screen having a metallic frame comprising a pair of bars each formed of sheet metal folded longitudinally upon

itself, and a second pair of bars, each composed of sheet metal folded longitudinally upon itself, and having its folded end portions inclosing the folded end portions of the other bars, said second pair of bars being bent longitudinally where they inclose the other bars, thereby bending the inclosed folded portions thereof transversely and forming the corners of the frame, substantially as described.

2. A window - screen having a metallic frame comprising a pair of bars each formed of sheet metal folded longitudinally upon itself, and a second pair of bars each formed of sheet metal folded longitudinally upon itself, the folded ends of said first pair of bars extending within the folded ends of the second pair of bars, and engaging the fold thereof, said second pair of bars being bent longitudinally throughout their length, thereby bending the folded end portions of the other bars transversely and forming the corners of the frame, substantially as described.

3. A window - screen having a metallic frame comprising a pair of bars formed of sheet metal, and a second pair of bars each formed of sheet metal folded longitudinally upon itself, and inclosing the ends of said first pair of bars, the folded portions of said second pair of bars which inclose the ends of said first pair of bars being given a plurality of longitudinal bends, thereby giving the inclosed portions of the other bars a plurality of transverse bends and locking said bars together, substantially as described.

4. A window-screen comprising among its members, a section of screen fabric, a pair of bars engaging opposite edges of said fabric, each consisting of a strip of metal folded longitudinally on itself and inclosing marginal portions of the fabric, and a second pair of bars, similarly formed, and inclosing marginal portions of the fabric and the folded end portions of said first-named bars, and disposed perpendicularly thereto, said second pair of bars being each bent longitudinally throughout their length, substantially as described.

5. A window-screen comprising among its members, a section of screen fabric, a pair of bars engaging opposite edges thereof, each consisting of a strip of metal folded longitudinally and inclosing marginal portions of the fabric, said bars being longitudinally bent, to secure the fabric therein, and a second pair of bars, similarly formed, inclosing marginal portions of the fabric and the folded end portions of said first-named bars, and disposed perpendicularly thereto, said second pair of bars being each bent longitudinally throughout their length to secure them to the fabric and to said first-named bars, substantially as described.

6. A sliding extensible metallic screen, comprising two screen - sections, each com-

posed of a section of screen fabric, vertical bars of sheet metal secured thereto, and horizontal bars each consisting of a strip of sheet metal folded longitudinally and inclosing the 5 ends of said vertical bars, said horizontal bars being given a plurality of bends longitudinally throughout their length to form retaining and guiding portions, and to secure the vertical bars thereto, the retaining and 10 guiding portions of one screen-section having a sliding engagement with the retaining and guiding portions of the other screen-section, substantially as described.

7. A sliding extensible metallic screen 15 comprising two screen-sections each composed of a section of screen fabric, vertical bars engaging opposite edges of said fabric each consisting of a strip of metal folded longitudinally and inclosing marginal portions 20 of said fabric, said bars being bent longitudinally to unite them to said fabric, and a pair of horizontal bars of similar form inclosing marginal portions of the fabric and the folded ends of said vertical bars, said horizontal 25 bars being given a plurality of bends longitudinally throughout their length to form retaining and guiding portions, the re-

taining and guiding portions of one screen-section having a sliding engagement with the retaining and guiding portions of the other 30 section, substantially as described.

8. A sliding extensible metallic screen, comprising two screen-sections each composed of a section of screen fabric, vertical bars engaging opposite edges of said fabric 35 each consisting of a strip of metal folded longitudinally and inclosing marginal portions of said fabric, said bars being bent longitudinally to unite them to said fabric, and a pair of horizontal bars of similar form inclosing 40 marginal portions of the fabric and the folded ends of said vertical bars, said horizontal bars being bent longitudinally throughout their length into substantially tubular form, the tubular portions of one screen-section 45 having a sliding engagement with those of the other screen-section, substantially as described.

In testimony whereof I affix my signature in the presence of two witnesses:

ALBERT A. DAY.
